UNITED STATES PATENT OFFICE

JOSEPH A. METZGER, OF BUFFALO, NEW YORK

TOY GUN

Application filed December 5, 1931. Serial No. 579,251.

This invention relates to improvements in toy guns, and has more particularly reference to a gun for shooting rubber or other stretchable bands, also cardboard squares or the like.

The primary object of my invention is to provide a simple and inexpensive toy gun of the type mentioned, which also has utilitarian features in that the rubber band may be held captive at one end of the gun and utilized for destroying flies and other insects.

Another object of my invention is the provision of a gun formed wholly of sheet metal, which can be easily stamped and the parts quickly assembled.

A further object of my invention is to provide means whereby the rubber band or bands associated with the gun may be projected under varying tensions so as to drive the bands varying distances.

A still further object of my invention is to provide means for retaining rubber bands, or cardboard or similar flat objects used as projectiles for the gun, captive to the gun so that they can be retrieved from the point from which they are projected.

With the above and other objects in view to appear hereinafter, the invention consists in the novel features of construction, and in the arrangement and combination of parts to be hereinafter described and more particularly pointed out in the subjoined claims.

In the drawing:

Fig. 1 is a side elevation of the gun, showing associated therewith as projectiles, both a cardboard or similar flat object and a rubber band, both being illustrated in the form in which they are used as free projectiles to be recovered for re-use from their place of landing.

Fig. 2 is a side elevation of a portion of a gun viewed from the side opposite that shown in Fig. 1.

Fig. 3 is a view of the gun with one of the side members removed, illustrating the parts within and partly within the casing of the gun.

Fig. 4 is an enlarged cross section taken on line 4—4, Fig. 1.

Fig. 5 is a detached perspective view of the

trigger mechanism, including the control spring for the same and the band release carried thereby.

Fig. 6 is a cross section taken on line 6—6, Fig. 1.

Fig. 7 is a detached perspective view of the spring retainer associated with the band-tensioning device.

Fig. 8 is a section taken on line 8—8, Fig. 5.

Fig. 9 is a side elevation of the band-tensioning device, showing the rubber band held captive thereto by means of a cord so that it can be retrieved from the position from which it is projected by the gun.

Fig. 10 is a detached perspective view of the band-tensioning device.

Fig. 11 is a side elevation of the outer end portion of the band-tensioning device showing the manner of holding a rubber or similar band captive thereon when using said band as an instrument of destruction for destroying flies or other insects.

The gun, as stated, is formed in the main of sheet metal stamped to provide two side members 12, 13, both being substantially of channel formation in cross section, and one of smaller dimension than the other so as to fit or nest into the latter; the channels being reversed to provide a rectangular space 14 which serves as the interior of the barrel 15 of the gun. The barrel extends along the greater portion of the length of the gun, and the side members are shaped at one end to form a hand-grip or stock 16 so that the device approaches in appearance the revolver type of weapon. The formation of the stock and the length of the barrel may, of course, be varied so as to have the appearance of a rifle. However, in the drawing illustrating my invention, the side members are continued rearwardly from the barrel 15, and each provided with a curved downward extension 17 forming the grip or stock of the gun. One of these side members is continued rearwardly in unchanneled or flat form from the inner end of the barrel, and its downward extension is also of flat formation. The other side member is continued rearwardly in flat form, and its downward extension 17 has a marginal flange 18 extending at one side from its

55

inner end downwardly, thence around the lower rounded end thereof, and thence upwardly in spaced relation to the barrel 15 to provide a trigger opening 19. The side 5 member 12 is provided with clips 20 in the form of lugs which are bent over the other side member and clip or hold the two side members in spaced relation. These clips prevent separation of the side members. The 10 side members are therefore spaced apart from one end of the gun to the other, and directly opposite the trigger opening a link opening 21 is provided.

The trigger opening 19 extends from the 15 inner flanged portion 18 of the hand-grip or stock to the inner end of the lower flanges on the barrel portion of the gun, and the link opening 21 extends from the outer flanged portion of the hand-grip or stock to the upper flanges on the barrel portion of the gun. Between the side members and in the space 20 between these openings the trigger mechanism and the release mechanism are arranged.

25 One of the side members, in the drawing member 13, has an upstanding flange 22 above the hand-grip or stock, and secured to the other side member 12, directly opposite, is a comparatively thin resilient clamp member 23; rivets 24, 25 being passed through said clamp member and through the spaced side members to fasten said clamp member to the body portion of the gun; and it may here be stated that these rivets are also utilized 30 as pivots for the trigger mechanism and release mechanism, respectively.

The clamp member 23 has its upper portion flexed inwardly, as at 26, so as to overhang the upper edge of the body portion of 40 the gun and normally it is in contact with the upstanding flange 22. Between this clamp member and the flange 23, a cardboard or other thin object 27 may be placed, said object, preferably square, being utilized as a 45 projectile and being firmly clamped by the flexible clamp member 23 when positioned in place, as clearly shown in Figs. 1 and 6.

50 The trigger 28 is positioned between the two side members and is also formed of sheet metal. It is shaped in any desired form and consists of a single piece of metal doubled upon itself, as at 29, to provide two spaced members 30, 31; member 30 being considerably larger than member 31 and having a 55 tapered upper end, near the apex of which a pivot opening 32 is formed. This pivot opening is adapted to have the rivet 24 passed therethrough, the rivet serving as a pivot for the trigger. Member 30 also has a tapered or narrowed portion at its lower end provided with a laterally-directed curved lug 33 forming a spring seat into which one end of a U-shaped trigger control-spring 34 is positioned which extends lengthwise within the 60 hand-grip or stock and has a laterally-di-

rected terminal 35 at its other end adapted to be entered in an opening formed in the flange 18 of the grip or stock.

The spring-retaining lug 33 also serves as a stop for the trigger in its forward or projecting movement, said lug engaging the flange at the front edge of the grip or stock 70 17, as clearly shown in Fig. 3. The free outer portion of member 31 of said trigger is narrowed and terminates in a hook or loop 75 36 adapted to be passed through a pivot hole 37 formed in one end of a link 38, which extends out through the link opening 21 in the hand-grip or stock, and at its outer end, this link is provided with a pivot hole 39.

80 40 designates a band release which is constructed of a strip of metal curved upon itself centrally between its ends to provide a substantially cylindrical portion on sleeve 41, opposite ends of the strip from which this band release is formed being directed in parallel lines from said cylindrical portion or sleeve 41 to form ears 42 which are spaced apart and between which the outer end of the link 38 is entered. One of these ears 42 has its lower marginal portion notched at its base, as at 43, said notch being formed by slitting the metal and utilizing the same as a pivot lug 44 which is continued on the circular line of the cylindrical portion or sleeve and passed through the opening 39 at the outer end of the link 38 and also through the opposite ear 42 which is notched, as at 45 for the purpose. The band release is therefore provided with an integral pivot for connection to the link, 90 and the ears 42 of said band release are provided with pivot openings 46 through which the other rivet 25 is passed, thus the rivets 24 and 25 serve, respectively, as pivots for the trigger and the band release.

95 Within the barrel portion of the gun is a tension element 47, also formed of sheet metal bent upon itself to provide a substantial bar of U-formation in cross section, slidably disposed within the barrel. The lower open 100 edge of this bar is provided with a series of notches 48, which may be referred to as adjustment notches, and anyone of which is adapted to be engaged by a retainer spring 105 49 formed of wire bent centrally between its ends to form a cross bar 50 and two side bars 51; the latter being spaced apart from the cross bar 50 a distance along their lengths and then brought in contact with each other, as at 52, the contacting portions of the spring 110 terminating in angular portions 53.

115 The spaced-apart portions of the side members 51 of this spring lie at opposite sides of the barrel, and are gradually directed underneath the barrel where they are clamped 120 by an inwardly-directed flange 54 formed on the side member 13 of the barrel, this clamp being directed underneath the contacting portion of the spring while the angular portions 53 of the spring are directed inwardly into 125 130

the barrel and clamped between the side members thereof.

In order that the contacting portions of the springs be held together, the inwardly-directed flange 54 is provided with an upwardly-directed retainer lug 55 which bears against one of the side members 52 of the spring. The contacting portions of these springs are therefore confined in four directions, thus providing a secure means of fastening the retainer spring in position.

The side members 12 and 13 of the barrel are also notched, as at 56, to enable the cross bar 51 of the spring to enter any desired notch in the tension device or bar 47. It will be clear that when the engaging end of the retainer spring is moved downwardly, as viewed in Figs. 1 and 3, the tension bar may be moved inwardly or outwardly, depending on the extent of projection desired for said bar from the forward or outer end of the barrel.

The tension bar 47 is provided with an oblique slot 57 near its outer end, the inclination of said slot being preferably downwardly and rearwardly, and between said slot and the outer end of the bar, an opening 58 is formed, the outer end of the bar being preferably curved, as at 59.

In Fig. 1 I have shown a rubber band 60 stretched over the barrel and stock of the gun and around the band release 40, or trip as it may be called, which release is normally in a position in which its axis is at right angles to the barrel 15. The cylindrical surface of said release or trip provides a substantial retention bearing for the rubber band, which is also passed around the outer end of the tension bar 47. When so positioned, this band is placed under tension and the degree of tension depends on the size of the band and the degree of projection of the tension bar. As the pull on this band is at right angles to the axis of the band release or trip sleeve 41, there is no possibility of the band becoming released until the position of said band release or trip is changed, and this requires the actuation of the trigger 28, which, upon being pressed inwardly through the trigger opening, causes the band release or trip sleeve to be swung on the rivet 25 serving as its pivot, due to the connection thereof with said trigger through the medium of the link 38. When the trigger is actuated, the trip sleeve 41 will be swung from the position in full lines to that shown in dotted lines, or beyond, depending on the degree of pressure exerted on the trigger. However, the upward and forward inclination of the trip sleeve will result in the rubber band riding over said sleeve and becoming released, with the result that it will be projected through the air under considerable force.

If desired to hold the band captive and yet enable it to be used as a projectile, it may

have a long string 61 attached to it, one end of the string being fastened to said band as shown in Fig. 9, and the other being fastened through the opening 58 in the tension bar. It will be quite apparent that the distance 70 the band is projected will depend entirely on the degree of projection of the tension bar from the barrel 15 of the gun.

In some instances a child will find amusement in the destruction of flies and other insects, in which case the device may serve as a fly swatter. In such cases the rubber band is stretched along a short region so as to reduce the thickness of the same, and at this region entered into the oblique slot 57 near 80 the outer end of the tension bar. When releasing the strain on the band after entering it in said slot, the rubber will expand and be retained within the slot under such expansion. The band may be stretched along the 85 barrel and stock of the gun, as already described, and when the trigger is actuated, will snap forward, but be held captive in the slot of the tension bar. The end of the band passed around the band release or trip sleeve 90 will snap forward under considerable force and can be accurately directed against any spot, such as may be occupied by a fly. This will result in instant destruction of the fly, or other insect.

It will be clear from the foregoing, that provision is also made for projecting cardboard squares or other thin projectiles retained in position above the stock of the gun and, while in Fig. 1 such a projectile 100 is illustrated at 27 and the rubber band is shown stretched around the outer extremity of the gun, it is to be understood that this band, when using such projectiles, will be held captive by entering the same in the slot 57; thus upon release of the rubber band from the band release or trip sleeve 41, it will be forcibly snapped against the inner edge of the projectile 27 and the latter projected under force a considerable distance.

It may here be stated that for indoor use the cardboard square, or other thin projectile, may also be held captive, a string being secured through the same and fastened in the opening 58 in substantially the same manner 115 as the rubber band illustrated in Fig. 9 of the drawing. When both the rubber band and the cardboard, or similar projectile, are held captive, no damage can be done although the toy may be used indoors, as the extent to 120 which the cardboard, or other similar device, is projected will easily be governed by the length of the string holding it captive.

Having thus described my invention, what I claim is:

1. A toy gun formed of sheet metal having two side members connected together to form a barrel and a grip or stock, said members having portions channel-shaped and reversed one within the other to form said bar- 130

- rel, one of said side members having retainer lugs at the outer edges of the flanges of its channeled portions to retain the two side members in nested condition.
5. 2. A toy gun formed of sheet material having a barrel and a stock and an integral flange extending upwardly from said stock at one side of the gun, a flexible retainer element at the other side of the gun co-acting with 10 said flange to retain a flat projectile between the two, said flexible retainer element being fastened to the gun by means of two spaced-apart rivets extending through the gun, a band-release pivotally arranged on the gun 15 and having a portion extending thereinto and for which one of said rivets serves as a pivot, said band-release serving with the outer end of the barrel to retain a rubber band under tension on the gun, a trigger within said 20 gun for which the other of said rivets serves as a pivot, and a link connecting said trigger with said band-release, said trigger serving to actuate said band-release through the medium of said link so as to forcibly engage the 25 band stretched around the gun against the flat projectile.
3. A toy gun, comprising a barrel and a stock formed of spaced-apart side members, a trigger formed of a piece of metal bent upon 30 itself to provide two members spaced apart, one of said members being pivotally connected at its upper end and having its lower end provided with a curved spring-retainer lug, the other member being provided at its 35 free end with an integral hook, a band-release having a cylindrical portion and being pivotally connected between the sides of the gun, a link connecting said band-release with said trigger and connected to the hook thereof 40 and having one end positioned between the spaced members of said trigger, and a substantially U-shaped spring within the stock of the gun having one end engaging the curved lug of said trigger and its other end 45 fastened into the stock.
4. A toy gun, comprising a barrel and a stock having spaced-apart side members, a trigger formed of a piece of metal bent upon itself to provide two members spaced apart, 50 one of said members being pivotally connected at its upper end and having its lower end provided with a spring-retainer lug, the other member being provided at its free end with an integral hook, a band-release formed of a 55 strip of metal bent to provide a cylindrical portion and parallel flanges extending from one side of said cylindrical portion, said band-release having an integral pivot, a link having holes at opposite ends, one of which is 60 adapted to receive the hook of said trigger and the other the integral pivot of said band-release, said band-release being pivotally secured between the sides of said gun and having the pivot thereof extending through its 65 parallel flanges, said spring-retainer lug serv-
- ing as a trigger stop, and a U-shaped spring within the stock of the gun having one end engaging said spring-retainer lug and its other end fastened into the wall of the stock.
5. A toy gun, comprising a barrel and a stock having spaced-apart side members, a trigger pivotally arranged within said stock between said side members, a band-release formed of a strip of metal bent between its ends into cylindrical form and having parallel spaced-apart flanges extending from one side thereof, one of said flanges being notched and the metal of said notch being continued to form a portion of the curved wall of said cylindrical portion, said continued portion serving as a pivot, and a link connected to said trigger and having an opening at one end through which the pivot formed on said band-release is passed, said link being positioned between the parallel spaced-apart flanges of 75 said band-release and said flanges being pivotally retained between the side walls of the stock.
6. A toy gun, comprising a barrel and a stock having spaced-apart side members, a trigger pivotally arranged within said stock between said side members, a band-release formed of a strip of metal bent between its 80 ends into cylindrical form and having a pair of parallel spaced-apart flanges extending from one side thereof, one of said flanges being notched adjacent said cylindrical portion and the other flange having a portion of the metal thereof bent inwardly to form a continuation of the wall of said cylindrical portion and to enter the notch of the first-mentioned portion, also to serve as a pivot, a link entering said band-release and being positioned between the flanges thereof, said link having pivotal connection at one end with 85 said trigger and having an opening at its other end through which the pivot of said band-release is passed, and a pivot secured in the side members of the gun and passed through the flanges of said band-release near 90 their upper edges.
7. A toy gun having a barrel and a stock, trigger mechanism, a band-release arranged partly within said stock and projecting partly therefrom, means connecting said trigger mechanism with said band-release, and a tension bar adjustably arranged within said barrel, said tension bar being formed of a strip of metal bent upon itself to form two spaced-apart members and being provided with a series of spaced-apart notches near its lower edge, said barrel having a notch formed along its lower edge, a retainer spring secured to 95 said barrel and having a cross member adapted to enter the notch of said barrel and any one of the notches in said tension bar.
- In testimony whereof, I affix my signature.
- JOSEPH A. METZGER.
